(57) **CLAIM**

The ornamental design for a single handle faucet with pull-out spout, as shown and described.

DESCRIPTION

FIG. 1 is a front perspective view of the single handle faucet with pull-out spout showing my new design;

FIG. 2 is a rear perspective view thereof;

FIG. 3 is a top plan view thereof;

FIG. 4 is a right side elevational view thereof;

FIG. 5 is a front elevational view thereof;

FIG. 6 is a left side elevational view thereof;

FIG. 7 is a rear elevational view thereof; and,

FIG. 8 is a bottom plan view thereof.

The broken line showing of the handle in FIG. 1, the spray selection button in FIGS. 1-4, 6 and 7, and the faceplate and spray apertures in FIGS. 4-6 and 8, are for purposes of illustration only and form no part of the claimed design.
